UNITED STATES PATENT OFFICE.

JAMES R. CHALLEN, OF COLLEGEVILLE, PENNSYLVANIA.

ATTACHMENT FOR TELEPHONE-RECEIVERS.

No. 844,299.

Specification of Letters Patent.

Patented Feb. 12, 1907.

Application filed May 12, 1906. Serial No. 316,481.

To all whom it may concern:

Be it known that I, JAMES R. CHALLEN, a citizen of the United States, residing in Collegeville, Pennsylvania, have invented certain Improvements in Attachments for Telephone- Receivers, of which the following is a specification.

The object of my invention is to provide a telephone-receiver with a simple, cheap, and efficient attachment which will serve to exclude local sounds from the ear and will be free from any tendency to cause injury to the delicate organs of the middle and inner ear. This object I attain in the manner hereinafter set forth, reference being had to the accompanying drawings, in which—

Figure 1 is a perspective view of one form of telephone-receiver with attachment in accordance with my invention. Fig. 2 is a transverse section of the same, on an enlarged scale. Fig. 3 is a view of a retaining-ring constituting one of the elements of my attachment. Fig. 4 is a view similar to Fig. 2, but illustrating a modification of the invention; and Fig. 5 is a sectional view of the receiver-cap, illustrating still another modification.

Aurists generally recognize the extreme danger of introducing foreign substances into the middle and inner ear, because the delicate organs therein contained are very susceptible to injury from such cause, and for this reason the provision of a telephone-receiver with anything in the nature of a tubular projection of relatively small diameter is to be avoided. In carrying out my invention, therefore, I provide the receiver with a centrally-disposed and centrally-apertured dome, of soft rubber or other elastic material, whose convex face projects beyond the face of the receiver and is therefore adapted to enter the outer ear and because of its elasticity and flexibility to conform to the contour of said outer ear so closely as to practically exclude local sounds which would interfere with the proper flow of the sound-waves from the vibrating diaphragm of the telephone-receiver to the tympanum of the ear, this result being attained without projection of any element of the attachment from the outer into the middle ear, and there-

fore without risk of injury such as would be caused thereby.

In the drawings, 1 represents the casing of the receiver; 2, the electromagnet the reinforced; 3, the diaphragm, and 4 the annular cap or face-plate, which is secured to the casing 1 and serves to retain the diaphragm in place thereon. The concavo-convex soft-rubber dome 5 has a central aperture 6 in its outer portion and is seated at the base upon the face of the cap 4, said base having in that construction of the dome which is shown in Fig. 2 an inwardly-projecting flange 7, which is confined against the face of the cap 4 by means of a metal ring 9, provided on its inner edge with a series of projecting spurs or barbs 10, which pass through the central opening 11 of the cap 4 and are bent outwardly against the inner face of said cap. 70

In that construction of the attachment shown in Fig. 3 the inwardly-projecting base-flange 7 of the dome is dispensed with, and the confining-ring 9 has in addition to the inner spurs 10 an outer series of spurs or barbs 75 12, which engage the dome near the base of the same, and therefore serve to confine said base of the dome closely to the outer face of the cap 4.

The dome shown in Fig. 5 has the inwardly-projecting flange 7, provided with a neck 13, integral with the flange, this neck passing through the opening 11 of the cap and having at its inner end a flange 14, which overlaps the inner face of said cap, the elasticity 85 of the neck 13 permitting the flange to be passed through the opening 11 in applying the dome to the cap.

I claim—

1. The combination of the receiver-cap, 90 the elastic dome having its base seated against the outer face of said cap and a ring engaging said base portion of the dome and having spurs or barbs whereby it is secured to the apertured central portion of the cap. 95

2. The combination of the receiver-cap, the elastic dome having an inwardly-projecting base-flange bearing against the outer face of said cap, and means for securing said base-flange to the apertured central portion of the cap. 100

3. The combination of the receiver-cap,

the elastic dome having an inwardly-projecting base-flange bearing against the outer face of said cap, and a ring bearing on said base-flange and having spurs or barbs whereby it is secured to the apertured central portion of the cap.

5 In testimony whereof I have signed my

name to this specification in the presence of two subscribing witnesses.

JAMES R. CHALLEN.
